UNITED STATES PATENT OFFICE.

ALBERT M. McMILLAN, OF RIVERDALE, MARYLAND.

PRINTING-PRESS CHASE.

Application filed August 6, 1926. Serial No. 127,672.

My invention relates to printing press chases, and particularly to a chase structure adapted for use on job presses and the like to permit the printing of a relatively wider 5 impression than is ordinarily possible.

An object of this invention is to provide a chase structure which can be fitted for use in place of a standard chase, and which provides an offset to receive the side locking 10 quoins, thus accommodating a type form or cut of a width substantially equal to the inside width of the standard chase.

A further object resides in so constructing the chase that it can be used with facility upon an ordinary printing press, and that no part will interfere with the proper operation of the inking rolls or other mechanism of the press.

Still another object is to provide a chase 20 having an offset to receive the locking quoins, which offset is of a width corresponding substantially to the standard width of wooden or metal furniture, so that the offset can be readily filled when it is desired to use the structure as an ordinary chase.

With the above and other objects in view, it will be apparent to those skilled in the art, my invention includes certain novel 30 features of construction and combination of parts which will be set forth in connection with the drawing.

In the drawing:

Fig. 1 is a view in plan of my improved 35 chase with a printing form locked in place therein.

Fig. 2 is a fragmentary view of the lower side of the chase illustrating a slightly different manner of use.

Fig. 3 is a sectional view substantially 40 on line 3—3 of Fig. 1.

Fig. 4 is a fragmentary view showing a slightly modified form which the invention might take.

The top side piece 1 and the end pieces 45 2 and 3 are of substantially the form and construction of a standard chase, and the ends of the lower side bar 4 are shaped in the usual manner to fit behind the hooks or clips by which the chase is supported and held in the press.

In the present instance I have illustrated 55 a chase of substantially the proportions of a standard 10"x15" chase, and the modification and changes from the standard chase, as contemplated by my invention are

calculated to adapt the chase to print upon a card of substantially 11" in width. A popular type of job press is the 10"x15" size, and a popular and economical sheet 60 or card size is 11"x14", as this is a quarter sheet secured from one of the standard stock sizes.

With standard chases it is necessary to place the locking quoins between the upper 65 or lower side bars 1 and 4 and the type form or cut, and this necessarily limits the width of type matter which can be accommodated. With my invention I offset the middle portion 5 of the lower bar 4, intermediate the 70 end portions adapted to fit the hooks or clips of the press, and this offset is made sufficient to substantially accommodate the locking quoins 6 and 7. Little difficulty is encountered as to the length of the form, and ample 75 space is usually available for the locking quoins 8 and 9 at the ends of the standard chase. The inking rolls usually travel adjacent the lower edge of the chase, and it is perhaps preferable that the offset portion 5 80 be beveled on its outer front corner, as illustrated at 10 in Fig. 3.

Where the chase is to be used for a smaller 85 form it may sometimes be found desirable to lock the form by the use of quoins inserted adjacent the upper side bar 1, and it is therefore essential that the offset of the middle portion 5 be of a substantially standard type furniture width. In the present instance I have shown this in substantially a 90 proportion of four picas, but this might be varied as conditions require.

In the main embodiment I have shown the lateral extension between the end portions 4 and the offset middle 5 as being substantially 95 diagonal, but this offset branch can be made substantially right-angular as indicated at 11 in Fig. 4, and can be otherwise formed.

While I have herein shown and described only certain specific embodiments of my invention and have suggested only certain possible modifications it will be appreciated that changes and variations can be made in the form, construction and arrangement of the parts to suit different requirements of use, 100 without departing from the spirit and scope 105 of my invention.

I claim:

1. A printing press chase of substantially 110 rectangular frame having one of the sides thereof offset in its middle portion to receive locking quoins, the middle portion being off-

set a distance corresponding substantially to a width of standard type furniture.

2. A printing press chase comprising a substantially rectangular frame having its ends and one side of substantially standard form, the remaining side of the chase being formed at its ends to be of substantially standard form to fit the chase holding portions of a press and being offset outwardly

in its middle portion to accommodate locking quoins, the middle portion being offset a distance corresponding substantially to a width of standard type furniture and being reduced and beveled on its outer forward corner. 10

15 In testimony whereof I hereunto affix my signature.

ALBERT M. McMILLAN.
